UNITED STATES PATENT OFFICE

DELL J. LAHAY, OF CARNEY, MICHIGAN, ASSIGNOR, BY DIRECT AND MESNE ASSIGNMENTS, TO UNIVERSAL PLAYGROUND EQUIPMENT COMPANY, OF MENOMINEE, MICHIGAN, A CORPORATION OF MICHIGAN

ROUNDABOUT

Application filed January 2, 1930. Serial No. 418,057.

This invention relates to improvements in roundabouts and it consists of the matters hereinafter described and more particularly pointed out in the appended claims.

5 The primary object of the invention is to improve the actuating or propelling mechanism in devices of this kind, and which eliminates the use of crank, clutch and spring elements associated with the mast or center pole, 10 which elements soon become inoperative due to the excessive wear developed therein.

Another object of the invention is to provide an improved mounting for the actuating levers of the device, whereby bearings 15 of substantial length may be had for such levers, which bearings are disposed upon rigid upright posts secured to adjacent structural parts, in a manner securely holding them in the desired position.

20 These objects of the invention as well as others, together with the many advantages thereof, will more fully appear as I proceed with my specification.

In the drawings:—

25 Fig. 1 is a perspective view of a roundabout embodying the preferred form of my invention.

Fig. 2 is a fragmentary top plan view on an enlarged scale of a portion of the roundabout in the plane of one of the radial arms thereof.

30 Fig. 3 is a detail vertical sectional view through a portion of the roundabout as taken on the line 3—3 of Fig. 2.

35 Fig. 4 is a vertical sectional view through the central portion of the roundabout and through parts directly associated with the mast or center post thereof.

Fig. 5 is a horizontal detail sectional view 40 through the post of the roundabout as taken on the line 5—5 of Fig. 4.

Fig. 6 is a detail vertical sectional view on an enlarged scale as taken on the line 6—6 of Fig. 3.

45 Fig. 7 is a perspective view showing a modified form of the invention.

Referring now in detail to that embodiment of the invention illustrated in Figs. 1 to 6 inclusive of the drawings, 1 indicates as 50 a whole, the base of the roundabout adapted

to rigidly support an upright mast or center pole 2. The base includes a collar 3 (see Fig. 4) which comprises a hub 4 and a downwardly and outwardly inclined flange 5. Fixed to said flange 5 and extending downwardly and outwardly therefrom is a plurality of radially disposed legs 6—6 preferably four in number and disposed equal arcuate distances apart. The outer ends of said legs which are made of angle bar stock 55 are bevelled off to engage flatwise upon the ground or other suitable support. If desired, suitable flat feet (not shown) may be provided on said outer ends of said legs. The adjacent legs 6 are connected together 60 at a point between their ends by brace bars 7, while the diametrically opposite legs are also connected together by brace bars 8. The construction mentioned provides a strong rigid base having that spread which 65 insures stability.

Preferably the mast or center pole 2 is made from a length of steel tubing and its bottom end is securely anchored against movement in the hub or collar 4 of the spider 75 3 as by the cross pin 9. Associated with and directly above the collar 3 is a second collar 10 which includes a hub 11 and a horizontally disposed radial flange 12. The hub 11 of the collar 10 and the hub 4 of the collar 3 are 80 formed to provide coacting raceways for antifriction bearings 13 whereby the collar 10 has a thrust as well as a radial bearing on the collar 3.

Fixed to the flange 12 of the collar 10 are 85 the inner ends of a plurality of horizontally disposed, radially extending arms 14 preferably made of angle bar. Preferably there are eight of such arms employed and said arms are spaced equal arcuate distances apart. On the top end of the mast 2 is secured a bearing block 15 having a recess 16 in its top end. Associated with this block is a cap 17 including a centrally disposed boss 18 and a downwardly and outwardly extending flange 19. The boss 18 extends into the recess 16 and an antifriction thrust bearing means 20 is interposed between them. The cap 17 is provided with a central opening 17a normally 95 100

closed in any suitable manner whereby the bearing means 20 may be kept lubricated.

21 indicates a plurality of braces, one associated with each arm 14 and arranged to connect the outer end of each arm 14 with the cap 17. Each brace which is fixed at its top end to the underside of the cap flange 19, extends downwardly and outwardly therefrom to terminate in a horizontally disposed extension 22 engaged with and fixed to the outer end portion of an associated arm 14 as best shown in Fig. 3. As best shown in Fig. 6, the vertical flanges of the angle bars constituting the outer end portion of the arm 14 and the horizontal extension 22 of each brace 21 are engaged back to back and are secured together in this relation as for example by the rivets 23. If desired, these parts may be spot welded together. The outer end portion of said extensions and arms respectively have secured thereto, the end portions of straight, wooden seat boards 24-24 so that the roundabout takes on a substantially octagonal shape as is apparent. Should it be desired, said seat boards may be made segmental so that said boards would then provide a circular seat for the roundabout. The ends of adjacent seat boards engage upon and are secured to the horizontal flanges of the brace extension 22 and outer end of each arm 14 as by the bolts 25.

Associated with the seat boards are foot boards 26, arranged in sets, one for each seat board, and each set of foot boards are secured at their ends to substantially L-shaped brackets made up of sections 27 of inverted T irons and hangers 28 of strap iron. Preferably the inner end of each section 27 is fixed to an associated arm and its outer end is supported from said arm by the hanger 28 so that the foot boards stand at substantially the angle of the braces 21.

Rising from each alternate arm 14 a short distance inwardly from the associated seat boards is an upright post 29. The bottom end of said post is fixed directly to the arm 14 while near its top end, said post engages with and is secured to the associated brace 21 as best shown in Fig. 3. This post includes top and bottom bearing ears 30 and 31 respectively on that side adjacent the seat boards and in said ears is journaled the upright shaft or stem 32 of the actuating or propelling lever 33 to be again referred to. Each stem includes a head 34 having a thrust bearing on the ear 30 and said head is formed to provide arms 35 arranged at that angle which corresponds to the angle between adjacent seat boards. Fixed to said arms are the levers 33, so disposed as to bring one arm into a position convenient for actuation by the occupant of each seat. Thus as it is apparent occupants of adjacent seat boards may team up with respect to the same lever. These levers 33 are connected up to the mast

whereby rocking movement of said levers causes a rotation of the seat boards about the post in either direction as will soon appear.

Fixed to the mast or center pole 2 in substantially the plane of the arms 35, is an eccentric disc or cam 36 having inner and outer upright annular flanges 36^a and 36^b defining an annular groove 37 between them, adapted to hold a lubricant. Associated with said disc and operatively engaged upon the flanges thereof is a one-piece circular strap 38, which carries clips 38^a to engage the bottom surface of the eccentric to prevent displacement between said eccentric and strap. This strap covers the groove 37 and is provided with ears 39, one for each lever 33. In the strap 38 is provided a valve device 40 whereby lubricant may be introduced into the groove 37 when necessary.

Links 41 operatively connect each ear with an associated lever 33. In this respect it is pointed out that the inner end of each link is connected at its inner end to an associated ear 39 and the outer end of each link is pivotally connected to one of the arms 35 on the head 34 of a shaft 32. I find it desirable to connect two intermediate and opposite links to those arms 35, each on one end the same side of the associated pin 32 and to connect the two alternate and opposite links to those arms 35, each on the other and same side of the associated shaft 32 as best shown in Fig. 1. The inner end of one of said links is connected by a bar 42 with an ear 43 on the strap which in effect prevents jack knifing or undue folding of the links.

In operation, the children sit one upon each seat board facing toward the center of the roundabout and thus each child is in a position to grasp one of the lever arms 33. As one child pushes on one lever end, his or her companion pulls on the other one, it being apparent that the other children are doing likewise. Thus as each ear 39 of the strap comes into a position wherein its associated link is tangential or offset with respect to the mast or center pole, and said link is moved endwise in one direction or the other, the seat boards as an entirety are caused to revolve or rotate about the mast. The power is applied progressively as each seat board comes into a predetermined position with respect to the post so that each seat occupant must contribute equally with the others in maintaining the seat boards in rotation.

Instead of so arranging the seat boards that the children face the center pole I may provide a construction wherein two children may sit facing each other. Under such conditions, the supporting arms 14^a are arranged in pairs as are the braces 21^a therefor. On the outer ends of the arms 14^a I provide a double arrangement of seats 43^a each of which includes a back rest 44, there being a common platform or foot board 46 for the

seats. On the inner end of the platform or foot board is a U-shaped bracket 47 fixed at its top end to a cross bar 48 which connects the arms 14^a together.

5 Journalled in said bracket is an upright shaft or pin 32^a to the top end of which a bell crank like lever 49 is fixed. One arm 50 of said lever is disposed in a position between the seats while the other arm has connected 10 to it a link 41. Thus when the children occupying said seats push and pull upon the lever arm 50 in alternation, the structure described is caused to revolve or rotate about the mast.

15 The construction described is free from all clutch teeth or springs, which soon wear and get out of order. It provides a wholesome and healthy enjoyment for the children using the same and gives that exercise which 20 materially benefits them in many ways.

While in describing the invention I have referred in detail to the form, arrangement and construction of the various parts thereof, the same is to be considered merely as 25 illustrative so that I do not wish to be limited thereto except as may be specifically set forth in the appended claims.

I claim as my invention:—

1. A roundabout embodying therein, a 30 base, a mast thereon, a frame structure including seat members rotatively mounted with respect to the mast, an eccentric fixed to the mast, a strap rotatable on said eccentric, lever members arranged in operative 35 relation to the seat members and means operatively connecting each lever member with said strap one of said means comprising a link operatively engaged at its ends with said lever and strap respectively and a bar 40 connecting said strap with said link adjacent that end engaged with said strap.

2. A roundabout embodying therein, a base, a mast thereon, coacting radial arms and braces rotatively mounted with respect 45 to said mast, a seat member carried by said arms, an eccentric fixed to the mast, a strap rotatable on said eccentric, a rocking lever including a shaft arranged in operative relation with respect to the seat member, means 50 supported at least in part by said arms providing a bearing for the shaft and means operatively connecting the lever with said strap and comprising a link operatively engaged at its ends with said lever and strap 55 respectively and a bar connecting said strap with said link adjacent that end with said strap.

3. In a device of the kind described, a mast, 60 an eccentric fixed to said mast and having a part formed to provide an annular lubricant groove therein, a strap rotatable on said eccentric and covering said groove and means for preventing axial displacement between said strap and eccentric.

65 4. In a device of the kind described, a mast,

an eccentric fixed to the mast and having a pair of upright, radially spaced flanges on one surface to provide an annular groove therebetween, a strap rotatably engaged on said flanges and covering said groove and 70 having means whereby a lubricant may be introduced into said groove and means carried by the strap and adapted to engage the other surface of the eccentric to prevent axial displacement between said eccentric and 75 strap.

5. A roundabout embodying therein, a base, a mast thereon, an eccentric fixed to said mast, a strap rotatably mounted on said eccentric, a plurality of radial arms and associated 80 braces rotatively mounted with respect to the mast, an upright post fixed to one of said arms and associated braces, a rocking lever, coacting means on said post and lever providing the pivotal axis for the lever, a link connected to 85 said lever and extending inwardly toward the mast and operatively connected to said strap and a bar operatively connecting said strap and link whereby operating movement of the lever causes rotative movement of said arms and braces about said mast.

In testimony whereof, I have hereunto set my hand, this 24th day of December, 1929.

CERTIFICATE OF CORRECTION.

Patent No. 1,896,796.

February 7, 1933.

DELL J. LAHAY.

It is hereby certified that error appears in the printed specification of the above numbered patent requiring correction as follows: Page 3, line 56, claim 2, before "with" second occurrence insert the word "engaged", and line 67, claim 4, before "flanges" insert the word "annular"; and that the said Letters Patent should be read with these corrections therein that the same may conform to the record of the case in the Patent Office.

Signed and sealed this 25th day of April, A. D. 1933.

M. J. Moore,
Acting Commissioner of Patents.
